Application June 13, 1934, Serial No. 730,512
In Sweden July 6, 1933

5 Claims. (Cl. 114—208)

This invention refers itself to anchors for ships and aircrafts. More specifically this invention relates to anchors without stock and provided with a plurality of flukes.

- 5 The principal object of this invention is to provide an anchor the weight of which is rather small in consideration of its gripping ability as compared with anchors of the types hitherto known.
- 10 Another object of this invention is the provision of an anchor that will engage the bottom immediately after being "cast" whereby a firm hold will be established within a short distance from that point, where the anchor was dropped.
- 15 A further object of this invention is the provision of an anchor which will not drag even if change in wind or stream causes the ship to swing about the anchor, so that the anchor is caused to capsize.
- 20 Still an object of the invention is the provision of an anchor the gripping efficiency of which is not dependent on the weight of the chain but will operate successfully in connection with a chain or rope, the size of which is suitable to withstand the stress set up therein solely by the load exerted by the ship proper.

Further an object of the invention is to provide an anchor capable of firmly holding on any bottom, wherein an anchor of any kind is possible to grip.

In the accompanying drawing an embodiment of the new anchor is illustrated, wherein

Figure 1 is a front elevation of the anchor.

Figure 2 is a longitudinal section of the anchor shown lying on the bottom, and Figure 3 is a plan view of the anchor viewed from above.

In the drawing 1 designates generally a stockless anchor, the shank 2 of which is pivoted by a pin 4 in a head 3. From the head 3 two rigidly connected arms 6 project in opposite directions, so that the arms 6 are turnable with the head 3. Each arm 6 carries a fluke 5 and in the free end of the main shank 2 there is a shackle 7 or the like for the anchor chain or rope 70. The main shank 2 is formed with an elongated aperture 8, in which aperture an auxiliary shank 10 is movable, which shank also is pivoted on the pin 4 so that the auxiliary shank 10 can oscillate in the main shank 2 in a plane parallel to the swinging planes of the flukes 5.

At the free end, the auxiliary shank 10 is forked to provide two rigid arms 11 each provided with a fluke 12, said arms being disposed in the swinging plane of the auxiliary shank 10. The head 3 is provided with abutments or shoulders

13 which limit the mutual movements of the two shanks 2 and 10. The shoulders 13 act to limit the angular movement of the flukes about the pivot pin 4 and they are also engageable with the shank 10 under certain conditions so as to cause the latter together with the flukes 12 carried thereby to be urged in one direction or the other. Such abutments can be provided on the arms 6 as well, as may be easily understood without need of a special figure in the drawing.

Because the flukes 5 are disposed laterally of the flukes 12 the first-mentioned flukes will be hereinafter referred to as the side flukes, and the other flukes will be referred to as the intermediate flukes in order to make a distinction between the two sets of flukes.

The length of auxiliary shank 10 measured from the apex of its flukes 12 to the center of its pivot 4 is greater than that of the side flukes. Thus the apexes of the intermediate flukes 12 will be more remote from the pin 4 than the apexes of the side flukes 5. Notwithstanding the intermediate flukes 12 are said to be rigidly connected by the arms 11, I do not limit myself to such a design, where the intermediate flukes are prevented from a swinging motion relatively to the arms 11 as I know that it is not novel to design anchors of the stock type in which the flukes can pivot against the arms which connect the flukes, and I wish to include such a design of the intermediate flukes also.

When the anchor reaches the bottom, it takes immediately the position illustrated in Figure 2 with the arms 11 of the auxiliary shank 10 disposed in a plane perpendicular to the bottom, whereby the downwardly directed intermediate fluke 12 instantly digs in on account of the dragging in the chain or rope 70. Said dragging exerts on the auxiliary shank 10, a pushing force, whereby the weight of the arms 11 with flukes 12 at the free hanging fore end of the auxiliary shank 10 causes the lowermost fluke 12 to dig in.

As stated the angular movement of the side flukes 5 is limited by engagement of the shoulders 13 with the shank 2 while the range of movement of the flukes 12 is also limited by engagement thereof with the adjacent portion of the shank 2.

When the wind or the stream changes, the new anchor operates under the same conditions as mentioned with the considerable advantage that the anchor immediately engages the bottom in its new position, if the change of the wind or the stream had caused the ship to ride

in the opposite direction forcing the anchor to capsize.

When the anchor reaches the bottom, the shorter side flukes 5 first falls down upon the surface of the bottom, the abutment 13 engaging the main shank 2. If then the intermediate fluke 12 has not begun to act, the abutment 13 presses against the auxiliary shank 10, and forces it downwardly.

10 The weight of the anchor chain is without importance in connection with the new anchor, hence a comparatively light wire rope can replace the usual heavy chain. Experience has shown that the new anchor gives a sufficient hold 15 on any kind of serviceable anchor bottom with an operative length of the rope 70 of only twice the depth, thus without need of the known chain line.

20 In common anchors of the stockless type the gripping resistance in the horizontal direction may be estimated as 9 to 12 times the weight of the anchor, while in an oldfashioned stock-anchor the same items may be 12 to 15 times the weight. This new anchor has proven itself to 25 stand a force of 37 to 40 times its weight.

On board, the new anchor can be housed in a hawse pipe of the type usual in combination with stockless anchors, though it sometimes may be convenient to make some modifications in the 30 design of the hawse pipe. Also it may be advantageous to make the pin 4 easily removable so as to detach the head from the shanks 2 and 10 for the purpose of facilitating storage in for instance small boats.

35 The new anchor makes it possible to anchor in narrow passages and streams on account of the aforesaid need of only short anchor ropes without risk of dragging.

I want to express my wish not to limit myself 40 exactly to the embodiment illustrated, but I am free to change the details in the design without to depart from the invention as set forth in the annexed claims. For instance the auxiliary shank 10 may be suspended not on the pin 4 of 45 the main shank and the side flukes, but on an independent pin parallel to pin 4 and disposed adjacent to said pin.

What I claim is:

1. In an anchor, a main shank, side flukes pivotally carried by one end of said shank for motion independently of the side flukes, an auxiliary shank pivotally connected adjacent said end 5 of the shank and extending throughout a substantial portion of the length thereof and beyond the side flukes, and intermediate flukes carried by the free end of said auxiliary shank.

2. In an anchor, a main shank, a head pivotally connected with one end of the shank, side flukes carried by said head, an auxiliary shank pivoted to the head for movement independent of the head and extending throughout a portion 10 of the length of the main shank, intermediate 15 flukes carried by the auxiliary shank, and shoulders on said head engageable with the auxiliary shank for imparting movement thereto.

3. In an anchor, a main shank adapted to be connected at one end with a flexible member, 20 side flukes arranged adjacent the opposite end of the shank, pivotally connected therewith and lying in a common plane containing their axis of pivoting, a relatively long auxiliary shank normally lying substantially within the main shank 25 and pivoted to swing independently of and parallel to the plane of motion of said side flukes, additional flukes disposed at the free end of said auxiliary shank and extending in a common plane perpendicular to the plane of motion of 30 said auxiliary shank.

4. In an anchor, a main shank having a longitudinal slot therein and adapted to be connected at one end with a flexible member, a head having two side flukes rigid therewith, an auxiliary 35 shank and two auxiliary flukes on the free end thereof, means for pivoting said shanks independently of each other on said head, the auxiliary shank being adapted to swing pivotally through said slot, said side flukes extending in a 40 general plane perpendicular to the plane in which said auxiliary flukes extend.

5. The device as claimed in claim 4 in which said auxiliary shank is longer than said side flukes.

45 NILS E. LUNDIN.
